JOHN HENRY HOLMES, OF NEWCASTLE-UPON-TYNE, ENGLAND.

APPARATUS FOR DISPENSING LIQUIDS.

1,134,536.

Specification of Letters Patent.

Patented Apr. 6, 1915.

Application filed June 14, 1912. Serial No. 703,627.

To all whom it may concern:

Be it known that I, JOHN HENRY HOLMES, a subject of the King of Great Britain and Ireland, residing at Portland Road, Newcastle-upon-Tyne, England, have invented 5 a new and useful Improvement in Apparatus for Dispensing Liquids, of which the following is a specification.

This invention relates to improved apparatus for dispensing liquids such for example as liquid soap in small quantities at a time, such quantities being of approximately equal volume and has for its object the provision of means for effecting this 15 purpose of a simple and inexpensive character adapted to insure certainty of action.

My invention consists in improvements in that class of apparatus in which, a container, a measuring chamber external thereto, a valve for controlling the passage of liquid from the container to the chamber, and another valve controlling the passage from the said chamber to the delivery, are so arranged that automatic operation is effected upon manual alteration of the capacity of the said measuring chamber; and provides for the association of the container with the measuring chamber in fixed relation with each other and further in the arrangement of parts whereby the delivery is effected by a single movement of the hand the refilling of the measuring chamber being effected automatically. In the case of liquid soap for example a small quantity is required to be delivered into the palm of the hand, and the apparatus herein described is specially suitable for use in this connection, although it is obvious it may be used for other materials such for example as scent 35 or oil.

In order that the invention may be the better understood I will now proceed to describe the same in relation to the accompanying drawings, reference being had to 45 the letters and figures marked thereon.

Like letters refer to like parts in the various figures, in which:—

Figure 1 is a sectional elevation of one form of my invention. Fig. 2 is a slightly 50 modified construction thereof.

The invention consists in an arrangement by which the liquid to be dispensed is stored in a container *a* and is drawn off from the external measuring chamber *a*¹ disposed below the said container *a*. The liquid is normally retained in the container in spite of

there being a hole *b* for the egress of the liquid by means of a valve *b*¹ opening outward which closes said hole *b*. The valve *b*¹ is pressed upward upon a seat *c* by a spring *d* so as to keep the valve closed so long as the apparatus is not being used for the extraction of the liquid. The seat *c* of this valve is adapted so that it may be pushed upward by the hand of the operator pressing upon a suitable projection *e* carried by the seat *c* and this action causes the valve *b*¹ to open and the liquid to be ejected on to the palm of the hand. To enable the seat *c* of the valve to be pushed upward as described, it may be carried in the center of a flexible diaphragm *f* rigidly supported at the edge, the natural elasticity of which causes it to bulge downward but it can be pushed in the opposite direction by pressure exerted by the hand of the operator. This is the arrangement shown in Fig. 1 so far as it is at present described.

As an alternative to this arrangement the valve seat *c* as shown in Fig. 2 may be 80 formed in a movable piston *c*¹ in a small open ended cylinder *k* attached to the container *a* such piston *c*¹ being pressed downward against a stop *k*¹ by a spring *l* but the piston can be pushed upward by the 85 hand of the operator.

To provide for the opening of the valve *b*¹ when the seat *c* is pushed upward and to insure the volume of the liquid ejected at each operation being approximately constant, the following additional mechanism is embodied in the apparatus. In Fig. 1 at a little distance above the flexible diaphragm *f* is arranged a rigid diaphragm *g* forming a false bottom to the container *a* and having 95 in its center a hole *h*¹ adapted to be closed by a valve *h*.

I arrange the valves *h* and *b*¹ to be mechanically operated as follows:—The lower valve *b*¹ opens downward, and is pressed upward and normally held in the closed position by the spring *d*. The valve *b*¹ has a stem *m* reaching upward and on this stem *m* is carried the valve *h* which closes the hole *h*¹ in the fixed diaphragm *g* or the upper 100 end of the cylinder *k*. In the normal position of the parts, this valve *h* is open and is disposed a little distance from its seat so that the liquid from the container *a* above may flow through. When the operator exerts sufficient upward pressure upon the lower valve seat *c* he raises it together with 105 110 115

its valve b^1 , valve stem m and upper valve h carried thereon, until the upper valve h closes and prevents further valve motion. A continued upward movement of the hand results in the opening of the lower valve b^1 , a diminution in volume of the space a^1 and the consequent ejection of the liquid. On the return stroke by spring pressure the lower valve b^1 first closes immediately followed by the opening of the top valve h thus allowing the flow of liquid from the container a to take the place of that displaced from the space a^1 . It will be understood that the amount of liquid ejected at one stroke depends upon the reduction of volume of the space between the valves b^1 and h after the upper valve h has closed and such reduction may be varied by altering the length of stroke.

20 It is obvious that the device may be adapted for use with a bottle so that by inverting the bottle the extraction function can be carried out by hand pressure on the device.

25 Having thus fully described my invention, I claim as new and desire to secure by Letters Patent:—

1. An apparatus for dispensing liquids comprising in combination, a container, a delivery valve seat rigidly mounted on the bottom of said container, a valve h adapted to open by a downward movement, a closed chamber of variable capacity rigidly attached to and below said container for receiving liquid from the said delivery valve h , externally operated means for varying the capacity of said closed chamber; and outlet valve b on said closed chamber mechanically connected with said delivery valve to prevent a continuous flow of liquid from said chamber; a movable seat for said outlet valve mounted on the said means for varying the capacity of the said closed chamber to allow the ejection of the liquid from the said chamber, means for applying hand pressure to the said movable valve seat to cause the discharge of liquid past the same from the said chamber to the exterior of the apparatus, and yielding means associated with said valves for counteracting the downward pressure of the liquid, substantially as described.

varying the capacity of the said closed chamber to forcibly eject the liquid from the said chamber, means for applying hand pressure to the said movable valve seat to cause the discharge of liquid past the same from the said chamber to the exterior of the apparatus, and means associated with said valves for at times counteracting the downward pressure of the liquid, substantially as described.

2. An apparatus for dispensing liquids comprising in combination, a container, a delivery valve seat rigidly mounted on the bottom of said container, a valve h adapted to open by a downward movement, a closed chamber of variable capacity rigidly attached to and below said container for receiving liquid from the said delivery valve h , externally operated means for varying the capacity of said closed chamber; and outlet valve b on said closed chamber mechanically connected with said delivery valve to prevent a continuous flow of liquid from said chamber; a movable seat for said outlet valve mounted on the said means for varying the capacity of the said closed chamber to allow the ejection of the liquid from the said chamber, means for applying hand pressure to the said movable valve seat to cause the discharge of liquid past the same from the said chamber to the exterior of the apparatus, and yielding means associated with said valves for counteracting the downward pressure of the liquid, substantially as described.

In testimony whereof I have signed my name to this specification in the presence of two subscribing witnesses.

JOHN HENRY HOLMES.
